DESIGN FOR A CLEANSING-FILM DISPENSER OR SIMILAR ARTICLE

William J. Schepp, Ridgewood, N. J.

Application November 7, 1939, Serial No. 88,120

Term of patent 14 years

To all whom it may concern:

Be it known that I, William J. Schepp, a citizen of the United States, residing at Ridgewood, in the county of Bergen and State of New Jersey, have invented a new, original, and ornamental Design for a Cleansing-Film Dispenser or Similar Article, of which the following is a specification, reference being had to the accompanying drawing, forming part thereof.

Referring to the drawing:

Fig. 1 is a view in perspective of the cleansing-film dispenser or similar article embodying my new design; and

Fig. 2 is a side elevational view of the article shown in Fig. 1.

I claim:

The ornamental design for a cleansing-film dispenser or similar article, as shown.

WILLIAM J. SCHEPP.
